UNITED STATES PATENT OFFICE

2,175,330

HEATING APPARATUS

Oscar G. Watt, Tulsa, Okla.

Application December 14, 1938, Serial No. 245,715

13 Claims.

(Cl. 4—1)

This invention relates to improvements in a combined pedestal cabinet and heating unit, and more particularly to a pedestal cabinet for use with a lavatory basin. The present application is a continuation-in-part of my application Serial No. 216,349, filed June 28, 1938. The primary purpose of the present invention is to simplify and improve the structures shown in my above-mentioned application.

10 In many sections of the country where natural gas and individual heaters are employed for home heating purposes, the bath room of the average home is heated by a small gas heater, usually having an open flame. Many disadvantages are 15 incident to this type of heating for a bath room, in that the heater not only takes up space in a small room but is usually placed in a position where a bather may accidentally come in contact with the same and be burned. Furthermore, in 20 the extreme cold months, individuals have a tendency to leave the heater on during the night in order to keep the bath room heated at all times. This is a source of danger as there is a possibility of the flame being blown out and endangering 25 the occupants of the house. Furthermore, this type of heater has many aspects of a fire hazard due to a bather's tossing a towel or article of clothing on or near the gas heater.

Like in my pending application I have by my 30 new improvements eliminated the disadvantages of present day bath room heaters and I will now describe such improvements in detail in connection with the accompanying drawings in which:

Fig. 1 is a perspective view of a pedestal cabinet 35 and lavatory basin viewed from the front end with the door of the cabinet open.

Fig. 2 is a similar view looking toward the rear of the cabinet.

Fig. 3 is a side elevation partly in vertical section and showing the manner of connecting the pipes of the lavatory basin and heater to the 40 circulating system of the home, the section being taken on the line 3—3 of Fig. 4.

Fig. 4 is a transverse vertical sectional view 45 taken on the line 4—4 of Fig. 3.

Fig. 5 is a perspective view of the heater housing or unit shown detached from the cabinet.

Fig. 6 is a bottom plan view of the unit shown 50 in Fig. 5.

Fig. 7 is a detail perspective view of one of the upper corners of the cabinet and showing the adjustable means employed in mounting the lavatory basin on the cabinet.

55 Fig. 8 is a front elevation partly in transverse

section of a simplified modification of the invention.

Fig. 9 is a side elevation of the same partly in longitudinal vertical section.

Referring first to the structures shown in Figs. 5 1 to 7 inclusive, 10 designates a cabinet made of any suitable material and preferably of enameled sheet metal. The cabinet has supporting legs 11, a front door opening 12, and upper rear opening 13 and a lower rear opening 14. As best shown 10 in Fig. 4, the bottom of the cabinet has an opening 15 for the entrance of cold air into the heating unit 16.

The opening 12 is normally closed by a front door 17 and each side of the cabinet has a grille 15 work or louvre section 18 for the discharge of hot air through the sides of the cabinet.

The unit 16 may be of U shape as shown in the drawings, that is provided with a hollow housing consisting of a cross portion 19 and upwardly 20 extending arm or flue portions 20, the latter terminating in curved top portions or hoods 21, the edges of which snugly engage the inner surfaces of the side walls of the cabinet, and the portions 21 functioning to direct the heated air through 25 the louvre portions 18. It will be apparent that the unit 16 may be integral with or removable from the cabinet 10.

At the rear of the unit 16 the arms or flues 20 are extended as shown at 22 so as to provide flue 30 portions having their discharge ends 23 in register with the rear opening 13 of the cabinet so that the heated air will not alone be discharged through the sides of the cabinet but also at the upper portion of the rear of the cabinet. 35

Any suitable type of heater 24 is arranged in the cross portion 19 of the housing but I preferably employ a hot water radiator type heater, and hook the same up by a pipe 25a with the pipe 25 which supplies hot water to the faucet 26 of the 40 plumbing fixture or lavatory basin 27. A two-way cock 28 is interposed in the piping for the purpose of cutting the radiator either into or out of the system without disturbing the flow or circulation of hot water to the faucet 26. Such 45 piping may be arranged as disclosed in my previous application.

Due to the U-shaped structure of the unit 16, there is a space 29 between the flues 20 for the accommodation of the drain pipe 30 and the two- 50 way valve 28.

The fixture or basin 27 may be of conventional type and in accordance with the present invention it is supported directly by the cabinet. For this purpose each one of the upper corners of 55

the cabinet is provided (Fig. 7) with a threaded block 31 through which passes a vertically disposed screw 32, the basin resting directly on such screws, and of course, as the screws are vertically adjustable they can be set to support the basin in the desired position. For steadyng purposes, adjustable screws 33 extend from the sides of the block 31 and they engage the inner surface of the apron or skirt 34 of the basin. At this point it will be noted that the lower edge of such skirt, at the sides of the cabinet, is positioned above the louvre sections 18. It will be understood that the basin can be made integral with the cabinet if so desired.

In use, if the valve 28 is set to cause hot water to travel through the radiator 24, it will be obvious that cold air will enter the bottom of the unit 16, be heated and then will be discharged through the louvre structures 18 and through the discharge ends 23 of the flues at the rear of the cabinet.

As the outer walls 35 of the heater are spaced from the side walls of the cabinet, this structure will function in a measure to insulate the cabinet and thereby prevent the burning of any one coming in contact with the exterior of the cabinet. The hoods 21 also function as shields to prevent the heated air from heating the basin 27; in other words, to insulate the basin.

In the embodiment of the invention illustrated in Figs. 8 and 9, the lavatory basin 40 may be supported in the same manner, as shown in Figs. 4 and 7, but I eliminate the housing unit 16 entirely and thereby reduce the cost of the structure and simplify the same. In this modification, the cabinet 40a is provided with a horizontal partition 41 which is positioned below the basin 40 and functions with the walls and bottom of the cabinet to form a heater compartment 42 which has louvre sections 43 and 44 arranged respectively in the sides and rear of the cabinet below the partition 41. Here also the cabinet may have a doorway 45 closed by hinged door 46.

Below the heater 47, which is positioned in the compartment 42, the bottom of the cabinet has an opening 48 for the entrance of the air to be heated, and of course, after the air is heated it will be discharged through the louvre sections 43 and 44.

Obviously my improvements may be used with other types of plumbing fixtures such as kitchen sinks, wash tubs, or the like.

While I have disclosed what I now consider to be preferred embodiments of the invention in such manner that they may be readily understood by those skilled in the art, I am aware that changes may be made in the details without departing from the spirit of the invention as expressed in the claims.

What I claim and desire to secure by Letters Patent is:

1. In a structure of the character described, a cabinet adapted to be arranged beneath a plumbing fixture and provided with an opening in its lower portion for the entrance of air, said cabinet having upper air discharge openings, a heater arranged in the cabinet between said entrance opening and said discharge openings, and means within the cabinet for causing the heated air to be discharged through said discharge openings and to prevent the air from discharging through the top of the cabinet.

2. In a structure of the character described, a cabinet adapted to be arranged beneath a plumbing fixture and provided with an opening in its

lower portion for the entrance of air, said cabinet having upper air discharge openings, a heater arranged in the cabinet between said entrance opening and said discharge openings, and means within the cabinet for causing the heated air to be discharged through said discharge openings and to prevent the air from discharging through the top of the cabinet, said means including a substantially U-shaped wall.

3. In a structure of the character described, a cabinet adapted to be arranged beneath a plumbing fixture and provided with an opening in its lower portion for the entrance of air, said cabinet having upper air discharge openings, a heater arranged in the cabinet between said entrance opening and said discharge openings, and means within the cabinet for causing the heated air to be discharged through said discharge openings and to prevent the air from discharging through the top of the cabinet, said means comprising a substantially horizontal partition arranged within the cabinet.

4. A cabinet adapted to be arranged beneath a plumbing fixture of a bath room and provided with a lower air inlet and upper air outlets, a substantially U-shaped hollow housing arranged in the cabinet and having flue portions in communication with said air outlets, said unit also having an opening communicating with said air inlet, and a heater arranged within said unit.

5. A cabinet adapted to be arranged beneath a plumbing fixture of a bath room and provided with a lower air inlet and upper air outlets, a substantially U-shaped hollow housing arranged in the cabinet and having flue portions in communication with said air outlets, said unit also having an opening communicating with said air inlet, and a heater arranged within said unit, each flue having a hood at its upper end abutting against the inner surface of the cabinet.

6. A cabinet adapted to be arranged beneath a plumbing fixture of a bath room and provided with a lower air inlet and upper air outlets, a substantially U-shaped hollow housing arranged in the cabinet and having flue portions in communication with said air outlet, said unit also having an opening communicating with said air inlet, and a heater arranged within said unit, said flues having their side walls spaced from opposite walls of the cabinet to provide insulation.

7. A cabinet adapted to be arranged beneath a plumbing fixture of a bath room and provided with a lower air inlet and upper air outlets, a substantially U-shaped hollow housing arranged in the cabinet and having flue portions in communication with said air outlets, said unit also having an opening communicating with said air inlet, and a heater arranged within said unit, said flues discharging through the rear wall of the cabinet.

8. A cabinet adapted to be arranged beneath a plumbing fixture of a bath room and provided with a lower air inlet and upper air outlets, a substantially U-shaped hollow housing arranged in the cabinet and having flue portions in communication with said air outlets, said unit also having an opening communicating with said air inlet, and a heater arranged within said unit, said flues discharging through opposite side walls of the cabinet.

9. In a structure of the character described, a cabinet, a plumbing fixture arranged at the upper end of the cabinet and supported by the cabinet, said cabinet having a lower air inlet and upper air discharge openings, a substantially U-

shaped hollow unit arranged in the cabinet and having a lower cross portion and upwardly extending flue portions, the cross portion being in communication with said air inlet, a heater arranged in said cross portion, the upper ends of the flue portions being in communication with said air outlets.

5 10. In a structure of the character described, a cabinet, a plumbing fixture arranged at the upper end of the cabinet and supported by the cabinet, said cabinet having a lower air inlet and upper air discharge openings, a substantially U-shaped hollow unit arranged in the cabinet and having a lower cross portion and upwardly extending flue portions, the cross portion being in communication with said air inlet, the upper ends of the flue portions being in communication with said air outlets, and a heater arranged in the cross portion of said unit, each flue portion being 15 arranged to discharge hot air through opposite sides and the rear wall of the cabinet.

15 11. In a structure of the character described, a cabinet, a plumbing fixture arranged at the upper end of the cabinet and supported by the cabinet, said cabinet having a lower air inlet and upper air discharge openings, a substantially U-shaped hollow unit arranged in the cabinet and having a lower cross portion and upwardly extending flue portions, the cross portion being 20

in communication with said air inlet, the upper ends of the flue portions being in communication with said air outlets, a heater arranged in the cross portion of said unit, the walls of the flue portions being spaced from opposite side 5 walls of the cabinet for insulating purposes, and each flue portion having a hood at its upper end which engages the inner surfaces of opposite walls of the cabinet.

10 12. In a structure of the character described, a cabinet, a plumbing fixture arranged at the upper end of the cabinet and supported thereby, a substantially horizontal partition arranged in the cabinet below said fixture and segregating the lower portion of the cabinet from the upper portion thereof, said cabinet having a lower air inlet and air outlets positioned above the same, and a heater arranged in the cabinet between the air inlet at said air outlet, the latter being arranged below said partition.

15 13. A cabinet adapted to be arranged beneath a plumbing fixture of a bathroom and provided with a lower air inlet and an upper air outlet, a substantially hollow housing arranged in the cabinet and having flue portions in communication with said air inlet, and a heating arrangement within said housing.

20 OSCAR G. WATT.
